UNITED STATES PATENT OFFICE.

WILLIAM H. DETWIELER, OF GREENFIELD, OKLAHOMA

THRESHING-MACHINE.

1,180,703.

Specification of Letters Patent. Patented Apr. 25, 1916.

Application filed August 9, 1912. Serial No. 714,170.

To all whom it may concern:

Be it known that I, WILLIAM H. DETWIELER, a citizen of the United States, residing at Greenfield, in the county of Blaine and State of Oklahoma, have invented a new and useful Threshing Machine, of which the following is a full, clear, and exact description, reference being had to the drawings hereto annexed.

Generally, this invention has reference to the art of threshing machines, and more particularly to the construction, association, and location of elements in such machines, as will create efficiency and increase results without a corresponding increase in effort.

It is an object of the invention to simplify structure and the arrangement thereof, and by so doing to increase efficiency and capacity.

It is also an object of the invention to so handle the bulk of the grain straws, and heads, after the initial breaking and whipping treatment that they receive at the feed or receiving end of the machine, that a greater portion of the full yield of grain will be separated and obtained therefrom.

It is another object of the invention to provide means for preventing congestion of the straw as it is carried through the machine.

Other objects of the invention, not here definitely stated, will become apparent from the following specification.

Within the purview of the invention, as expressed by the objects above stated, various forms and constructions of elements suitably associated in the production of a machine for threshing, may be employed, and one of such machines, constructed in a simple and practical manner, and one which probably will be used in practice, is illustrated in various views on the accompanying sheets of drawings forming a part of this specification, and whereon:

Figure 1 is a side elevation of the machine, the straw-stacker and certain other parts not necessarily connected with this invention being omitted. Fig. 2 is a similar view of an improved shaker employed in the machine.

Fig. 3 is a similar view of another shaker. Fig. 4 is a sectional view of the machine in the same direction. Fig. 5 is an enlargement of that portion of Fig. 4 at and around the point indicated by the arrow 5. Fig. 6 is an enlargement of that portion of Fig. 4 at and around the point indicated by the arrow 6.

Fig. 7 is an enlargement of that portion of Fig. 4 at and around the point indicated by the arrow 7, this figure being on still larger scale than Fig. 6. Fig. 8 is a perspective view of the parts shown in Fig. 7, thus being a view of the delivery end of the shaker shown in Fig. 3. Fig. 9 is a plan view of the parts shown in Fig. 7, and on the same scale. Fig. 10 is a perspective view of certain parts taken approximately in the same direction as Fig. 8, but at a longer range. Fig. 11 is a perspective view of a screen, taken in the same direction as Figs. 8 and 10, but at a closer range than either. Fig. 12 is a greatly enlarged reproduction of that portion of Fig. 5 lying within the circular dotted line 12. Fig. 13 shows an optional construction of parts shown in Fig. 12. For purposes of this description, the right-hand end of Figs. 1 to 7, 9, 12 and 13, is assumed to be the rear or delivery end.

Like characters of reference designate like parts throughout all the figures of the drawings.

The machine shown comprises, in part, an elongated casing or housing 14, which is contained within and supported by a skeleton frame 15, the rear end and lower portion of this casing being left permanently open except as partially closed by moving parts of the machine. The front end of the casing 14 is formed into a hopper 16 adapted to receive the grain straw. A toothed cylinder 17 is journaled transversely through the hopper 16, and a toothed concave-plate 18 is mounted under the cylinder to coact therewith in breaking up and whipping the grain straws and heads. A partial partition 19 depends from the upper wall 20 of the casing 14 in front of the cylinder 17 to prevent the straw from being whirled back out of the casing by the cylinder teeth 21.

A shaker 22, shown separately in Fig. 2, is mounted movably in the casing 14, and is supported by pivoted hangers 23 which connect it with said casing. A revolving beater 24, having radial wings 25, is journaled transversely through the casing 14 immediately in the rear of the cylinder 17, and is adapted to have a retarding and whipping effect on the straw thrown rearward above the shaker 22 by said cylinder. A second shaker 26, shown separately in Fig. 3, is likewise mounted in the rearward portion of

the casing 14, immediately below the shaker 22, and is hung to said casing by pivoted hangers 27. For imparting to the shakers 22 and 26 a fore-and-aft vibratory movement, a crank-shaft 28 is journaled transversely through the front portion of the frame 15, and connecting-rods 29 and 30, respectively, extend from the cranks of said shaft and pivotally attached to said shakers. 5 The shaft 28 is driven by any suitable means, preferably that well known in the art. Within the rear portion of the casing 14, and particularly under the rearward portion of the lower shaker 26, a riddle-box 31 is supported by hangers 32. For imparting to this riddle-box 31 a lateral vibratory movement, a rock-shaft 33 is journaled vertically in bearings 34, which are bolted to the frame 15. This rock-shaft 33 has a 10 radial arm 35 which imparts motion to the riddle-box 31 through a connecting-rod 36, and a second arm 37 which receives motion from the crank-shaft 28 through a connecting-rod 38. The riddle-box 31 is provided 15 with a screen 39, best shown in Fig. 11, which receives the grain and other matter that passes down through the open portion of the rear or lower shaker 26, and an air-fan 40 is provided to cause a more or less 20 forcible blast of air rearwardly through said riddle-box.

Upon delivery of the grain and other matter onto the screen 39, the air draft upward through said screen from the air-fan 40 resists the precipitation of a part of the lighter matter through the screen, the grain and portions of the heavier matter falling through the screen and toward and upon the forwardly inclined bottom 41 of the 25 riddle-box through the air blast. The separated grain, being the heavier matter passing through the riddle-box, passes forward down the inclined bottom 41 to final delivery from the machine through a laterally descending trough 42 formed in the lower front corner of said riddle-box, while such grain as has not been entirely freed from or is caught by the lighter matter is driven rearwardly up the inclined bottom 21 and 30 into a lateral delivery trough 43 formed across the lower rear corner of said riddle-box. The grain and matter thus ejected from the rear of the riddle-box by the air draft is carried upward and forward on 35 the outside of the casing 14 by an elevator 44, to be again delivered into the casing 14 onto the first or upper shaker 22 for re-agitation.

Since, in the threshing of Kafir corn, for 40 which this invention is primarily designed, only breaking or whipping operation of the cylinder 17 and concave-plates 18 is required, the delivery of the matter by the elevator 44 into the casing 14 is made rear- 45 wardly of said cylinder, and, in fact, rear-

ward of the beater 24 as shown, a stop-board 45 being provided and depending from the top 20 of said casing 14 to prevent the incoming matter from the elevator spout 46 being unduly fanned from 70 its normal course by said beater.

The construction and operation of the parts thus described does not differ materially from those found in other machines of this class, except in the location of the point 75 at which the elevator 44 delivers its contents into the casing 14, but they do coact with the newly constructed and arranged parts presently to be described in attaining the objects of the invention.

In the improved arrangement and construction of parts, approximately the front half 47 of the first or upper shaker 22 is disposed horizontally, but the rear half 48 is inclined upward at a small angle as it extends to the rear end of the machine. This upward inclination of the rear half 48 of the shaker 22 has the effect of partially retarding the progress of the straw, thereby allowing more time for a more complete 90 separation of the grain therefrom. The inclination of the rear half 48 of the shaker 22, however, is not such, with reference to the top 20 of the casing 14, as will ordinarily permit a congestion of the straw bulk, 95 which, when congestion obtains in devices of this character, finally renders such devices inoperative.

As best shown in Fig. 4, approximately the front two-fifths of the shaker 22 is provided with a bottom 49, which extends rearward into position to deliver its contents into the shaker 26. In further completing the construction of the shaker 22, a series of parallel ribs 50 are located transversely with 100 respect thereto, the ends of said ribs resting upon and being secured to the side pieces 51 of said shaker. In cross-section, each rib 50 is substantially one-quarter of the area of a circle, as best shown in Fig. 12, one face 105 52 of each rib lying upon the upper edges 53 of the sidepieces 51 while the other face 54 is disposed rearward and perpendicular to said lower face 52. The straw, as it comes from the cylinder 17, drops upon the ribs 110 50, and, under the influence of the vibratory movement given to the shaker 22, is worked gradually rearward and thoroughly 115 agitated to remove the grain.

In operation, the ribs, as arranged, have 120 the effect of rearwardly inclined teeth, moving the straw gradually rearward as stated; but, on account of the cylindrical surface 55 of each rib, the short portions of the broken straws are given a movement not produced 125 by other machines, with the result that a more complete separation of the seed is effected.

In actual practice, the shorter pieces of straw, during their travel over the ribs, and 130

by reason of the movement of the bulk of straw behind them, moving rearwardly from the cylinder 17, will cause the shorter pieces to pivot upon the upper corner 56 of each rib and assume some of the various positions indicated by the dotted lines in Fig. 12; the lower ends of the straws catching a new and lower hold upon the cylindrical surface 55 of the next rearward rib at each vibration, with the effect that the straws are tilted rearward, and over the corner 56 of each rib, when they will be allowed to pass on with the bulk and thereby prevent temporary retention of portions of the bulk which would increase congestion if the shorter pieces remained projecting upward from the ribs. This handling of the straw retards its passage through the machine sufficiently to allow a full separation of all grain, and the cylindrical surface of the ribs offers a minimum retard of the movement of the grain down through the shaker 22.

In Fig. 13 an optional form of rib is shown, the lines 57 indicating the rear faces 54 previously described. In this optional form of rib, a surface 58, in a horizontal plane, extends rearward from the line 57, tangent to the curved surface 55, these surfaces 58, when used, having the effect of allowing the straw to remain longer on the shaker 22 before its final delivery from the rear of the machine. All the matter passing through the ribs 50 of the upper shaker 22 is delivered onto the second shaker 26 for further treatment, the bulk of the straw passing off the rear end of the upper shaker and out of the machine.

The floor 59 of the front portion of the lower shaker 26 has its surface formed into transverse rearwardly inclined teeth 60, adapted to urge the matter rearward as the shaker vibrates, but the rear or remaining portion of said shaker is provided with a bottom screen 61 better shown in Figs. 7 to 9, this screen being directly above the riddle-box 31. The object of this screen 61 is to

permit the spherical Kafir corn seed, which is heavier than the chaff and other matter, to readily run down through openings therein 50 in streams into the riddle-box 31; and in the attainment of this object a screen for that purpose may be made with a suitable form of delivery troughs. In the present instance, however, in forming this screen 61, a blank 55 of sheet metal 62 is cut or slotted on lines 63 transversely of the screen, the portion 64 of the metal immediately in front of each slit being pressed upward and a portion 65 immediately in the rear being pressed 60 downward. In thus slitting and shaping the metal, a series of small forwardly-descending delivery troughs 66 are provided, with the result that the spherical Kafir corn seed will run down through said troughs 65 into the riddle-box. The trash that follows down through the screen 61 with the grain is caught and blown rearward by air which passes up through the riddle screen 39 from the fan 40.

Having thus described the invention, I claim:—

A threshing machine comprising in combination with means for introducing the grain thereto of a single upper screen for 75 separating the grain and chaff from the straw, and means for separating the grain from the chaff, said upper screen having a reciprocatory movement and extending 80 from a point immediately below the introducing means to a point in the rear of the chaff separating means, the rear portion of said upper screen being inclined upwardly at a slight angle, and comprising transverse bars, the forward surface of which is cylindrical.

Signed at Greenfield, in the county of Blaine, and State of Oklahoma, on this 20th day of July, 1912.

WILLIAM H. DETWIELER.
